BOTTLE HOLDER OR THE LIKE

Robley D. Palmer, Holyoke, Colo.

Application February 7, 1958, Serial No. 49,538

Term of patent 14 years

(Cl. D83—8)

The broken line representation of a baby bottle is for illustrative purposes only.

I claim:

The ornamental design for a bottle holder or the like, as shown and described.
